UNITED STATES PATENT OFFICE.

SHUICHIRO OCHI, OF TOYOTAMA, AND FUSAZIRO KOTERA, OF EBARA, JAPAN.

REFINING PROCESS OF SUGAR JUICE BY CHLORINATION.

No Drawing.

Application filed December 3, 1924. Serial No. 753,740.

This invention relates to a process for the refining of sugar juice by chlorination, more particularly to a process comprising the following successive steps, that is, chlorination 5 of sugar juice or liquid raw sugar by blowing chlorine gas into sugar juice or liquid at a temperature of not more than 55° C., removing the active chlorine and neutralization of the treated juice by adding an 10 alkaline material. It has for its object the decomposition of the colouring elements and other impurities contained in the juice by oxidizing action of active chlorine, so that the 15 said juice is bleached and refined more easily and more economically than by any other process hitherto known.

In this specification and claims, the word "juice" should be understood to mean that 20 extracted or taken from sugar canes, beet roots and/or other sacchariferous plants, or liquid of raw sugar made of such juice.

Before explaining the details separately under each particular, a general explanation is here attempted. The process generally speaking, is firstly to generate active chlorine in the juice to be treated, by blowing chlorine gas therein or by the like manner. Keeping the juice at a temperature of not more than 55° C., bleaching and refining of the juice to be completed while retaining it in acidic or neutral state. Secondly, activated charcoal is added in order to remove active chlorine, and thirdly or lastly, an alkaline material is added to the 35 juice to neutralize the same in such a degree as not to invite or prompt the formation of invert sugar. The juice thus refined may be treated to manufacture sugar by a method publicly known in the sugar industry.

Chemically speaking, it may be observed 40 that the infusion of chlorine in sugar juice may stimulate the inversion of sucrose as hydrochloric acid develops therein as well as active chlorine, and that the heat treatment of the solution that has become acidic will turn all the sucrose in the solution to invert sugar and destroy the attainment of the purpose, but the inventor's practical experience has demonstrated that such inverting effect is almost nil, when the quantity 45 of active chlorine used is so small as to just complete the bleaching with the heat so arranged as to be kept constantly below 55° C., and even if more or less inversion takes 50 place, such inversion is in no degree apprehensive from industrial point of view. It

is to be noted that the bleaching is perfectly accomplished in the above degree of heat; any stronger heat being found neither to improve nor to accelerate the bleaching. 60

Following the bleaching treatment already explained, it is now necessary to remove the chlorine which remains without participating in the bleaching operation, as otherwise it will derange or disturb the 65 process of neutralizing which follows. The method of active chlorine removal is attained by the aid of the catalytic action of activated charcoal, or any other carboniferous substances of porous construction capable of catalytic action. 70

After disposing of the chlorine as described before, the next operation is to neutralize the solution by mixing an alkaline agent in the same. This operation must be 75 done immediately after the above chlorine treatment as otherwise, if the solution is in a strongly acidic state, it will be turned into inverted sugar in the course of the subsequent operation, while if the solution is in 80 alkaline state, the bleached solution will show a brownish colour. The material to be used for neutralization of the solution may be any alkaline substance, such as oxides, or carbonate of alkali or alkaline earth material, or ammonia. The neutralizing agents may be added to the juice or solution after the infusion of chlorine, or may be added partly or wholly from the commencement of the treatment or during its course. 90

With respect to the use of chlorine, it is to be noted that while blowing it in the form of gas into sugar juice or liquid raw sugar is found most convenient, any of the following solutions may be substituted for a 95 part or whole of chlorine gas blowing, namely, water solution of chlorine, sugar juice solution of chlorine, acidic or neutral solution prepared by dissolving chlorine in a solution of alkali, such as lime, acidic or 100 neutral solution prepared by adding acidic substance, such as chlorine or carbon-dioxide to the water solution of bleaching powder, or the like which contains active chlorine. Or, chlorine gas may be successively generated in the juice by direct electric current through the same previously mixed with a quantity of chloride such as sodium chloride. Foregoing processes are illustrated by 105 a few examples as follows.

Example 1.—A solution consisting of 100 kilogrammes of raw sugar, having the shade

corresponding to No. 15 of Dutch standard dissolved in 70 kilogrammes of warm water, into which 75 litres (0.2 kilogramme in weight) of chlorine gas are blown while being constantly stirred up at the temperature of 20° C. will be quickly bleached, brown colour being entirely achromatized with only a slight yellow tint remaining. Next to the above treatment, a mixture of 1 kilogramme 10 of activated charcoal with the solution will remove the free chlorine, and on its being neutralized with a strong solution of caustic soda becomes colourless. This solution is evaporated in vacuum, by ordinary method. 15 Care should be taken at the same time, that the bleaching solution described above may not become alkaline in property.

An advantage may be gained in carrying out the method above described in the economy of chlorine when the sugar to be treated is to treat the raw sugar after having been washed in water so as to remove the molasses adhering or stuck to the material: but as it results in reducing the organic acid 25 salt in them, such method requires very great care at the time of the last neutralization: for if by carelessness or neglect the treatment to be given in acidic state however slight it may be, the loss will be greater than 30 by the treatment in which molasses have not been removed.

It is to be noted that in carrying out the bleaching according to the process above stated, a quantity of chlorine less than that 35 indicated in the above example 1 may be so used as to have the juice in semi-bleached condition and in such condition to be filtered through a charcoal filter. Or, the treatment may be reversed, that is to say, the juice may 40 be first filtered and then the bleaching process according to the example above cited may be applied. In both cases described, it will be found that the bleaching will be far more easily accomplished compared with 45 other chlorination methods.

Example 2.—In applying the chlorination process to the sugar juice in the condition as it is extracted from sugar cane or other sacchariferous plants, this invented process 50 is perfectly carried out in combination with other refining methods such as defecation, sulfitation, and carbonization. For instance, a small quantity of chlorine gas blown into the cane juice kept at a temperature lower 55 than 40° C. will make the impure matters coagulate and precipitate after which the juice is filtered, and activated charcoal is mixed in order to remove active chlorine. After the chlorine is thus removed, phosphate or

carbonization process may be resorted to, and manufacturing follows in a usual way. The quantity of chlorine to be blown into the juice varies greatly according to the quality of sugar juice and also depends upon whether or not a previous treatment was given. Taking cane juice as an example, 60 0.01 to 0.02 kilogramme of chlorine to 100 litres of the juice is sufficient for the purpose of refining. It is to be added that the above treatment may be made with success to the juice concentrated up to a certain stage of refining.

Example 3.—Bleaching of the juice previously refined by an ordinary method can be perfectly made by adding a suitable quantity of clear solution of bleaching powder, into which chlorine gas is blown, the temperature being kept to one degree below 40° C. to make the juice acidic or neutral state. 70 Following this treatment, activated charcoal is added and the resulting precipitate is filtered. If the product is found to be acidic, it should be neutralized by the addition of slaked lime.

Example 4.—The passing of direct electric current between electrodes of platinum or graphite through 100 litres of liquid raw sugar or juice whether in the original condition or a concentrated form with 0.03 kilogramme of sodium chloride added, will generate chlorine by electrolysis and the bleaching is thereby perfected. To the materials thus bleached, 0.05 to 0.01 kilogramme of activated charcoal is added and after being neutralized, manufacturing is carried out by 80 following usual methods.

What we claim is:—

1. A process of refining sugar juice comprising the combination of the following successive steps, chlorination of sugar juice 100 by blowing chlorine gas into the same at a temperature of not more than 55° C., removing the active chlorine therefrom and neutralization of the treated juice by addition of an alkaline substance.

2. A process of refining sugar juice comprising the combination of the following successive steps, blowing chlorine gas in sugar juice at a temperature of not more than 55° C., removing the chlorine therefrom by adding activated charcoal and neutralization of the treated juice by addition of an alkaline substance.

In testimony whereof we have signed our names to this specification.
